DESIGN FOR A TIRE INFLATOR

Archibald R. Moffett, Orinda, Calif.

Application April 19, 1948, Serial No. 145,805

Term of patent 14 years

(Cl. D52—1)

To all whom it may concern:

Be it known that I, Archibald R. Moffett, a citizen of the United States, residing at Orinda, in the county of Contra Costa and State of California, have invented a new, original, and ornamental Design for Tire Inflators, of which the following is a specification, reference being had to the accompanying drawing, forming part thereof.

Figure 1 is a view in perspective of a tire inflator, showing my new design;

Figure 2 is a top plan view of the same;

Figure 3 is a front elevation view of the same;

Figure 4 is a side elevation view of the same; and

Figure 5 is a rear elevation view of the same.

I claim:

The ornamental design for a tire inflator, substantially as shown.

ARCHIBALD R. MOFFETT.
